UNITED STATES PATENT OFFICE.

LAWRENCE G. ZESBAUGH AND CHARLES E. LARSON, OF MINNEAPOLIS, AND OWEN W. THOMAS AND SAMUEL FRYCKBERG, OF ST. PAUL, MINNESOTA, ASSIGNEES TO MARVEL MACHINERY COMPANY, OF MINNEAPOLIS, MINNESOTA, A CORPORATION OF MINNESOTA.

BORING-MACHINE.

1,322,213.

Specification of Letters Patent.

Patented Nov. 18, 1919.

Application filed May 8, 1917. Serial No. 167,302.

To all whom it may concern:

Be it known that we, LAWRENCE G. ZESBAUGH, CHARLES E. LARSON, OWEN W. THOMAS, and SAMUEL FRYCKBERG, citizens 5 of the United States, residing at Minneapolis (ZESBAUGH and LARSON), and St. Paul (THOMAS and FRYCKBERG), in the counties of Hennepin and Ramsey, respectively, and State of Minnesota, have invented certain 10 new and useful Improvements in Boring-Machines, of which the following is a specification.

Our invention relates to boring machines and has for its object to provide improved 15 and efficient mechanism for operating a boring bar for boring machines. It is an especial object of our invention to provide means for continuously rotating the boring bar and at the same time advancing it at 20 any desired speed from the point where it is substantially stationary up to the maximum rate of advance. In carrying out our invention we provide improved means, including a friction drive for controlling 25 both advance and reverse movement of the boring bar at any desired speed.

The full objects and advantages of our invention will appear in connection with the detailed description thereof and are particularly pointed out in the claim.

In the drawings, illustrating the application of our invention in one form,—

Figure 1 is a side elevation of a boring machine embodying our improvements. Fig. 35 2 is a top plan view of the same. Fig. 3 is a sectional elevation on line 3—3 of Fig. 2.

As illustrated, the machine comprises a base 10 to which is secured a table 11 having thereon, a central standard 12, rear 40 standard 13 and front standard 14. A face plate 15 is secured to a plate 16 on standard 14, a plate 17 on table 11 and a plate 18 on base member 10. To the face plate is connected for vertical sliding movement the 45 work-holding bracket 19 adjusted by hand screw 20 and having thereon the laterally adjustable table 21 controlled in its lateral adjustments by hand wheel 22.

Within the brackets 12 and 14 is journaled 50 a boring bar 26 upon which is splined a spiral gear 27 having the spline extended into a longitudinal groove 28 in boring bar 26. The spiral gear 27 is held between a portion 28' of bracket 12 and a sleeve col-

lar 29 surrounding the boring bar between 55 spiral gear 27 and bracket 14, as clearly shown in Figs. 1 and 2. The end 30 of the boring bar extends through an aperture in face plate 15, where it is fitted with a boring or milling head 31 which is adapted 60 to operate in a cylinder or other member 32 held upon work table 21. A rack bar 33 has its forward end swiveled to the rear end of boring bar 26, being held thereto by an end plate 34. The rack bar 65 extends rearwardly through a guide 35 above, and meshes with, a pinion 36 on a sleeve 37 which is journaled on a transverse shaft 38 mounted in rear bracket 13.

The machine is driven from fast and loose 70 belt pulleys 39 and 40 on a transverse shaft 41 on which is a spiral pinion 42 meshing with the spiral gear 27 on the boring bar 26, and by which said boring bar is rotated. The shaft 41 which is journaled in 75 upright 12 has on one end the pulleys 39 and 40 and on the other end a friction disk 43. Coöperating with friction disk 43 is a friction wheel 44 splined upon a shaft 45 which is journaled in brackets 46, 47 and 80 48 secured to table 11. A yoke 49, slideable on a rod 50 carried by brackets 46 and 47 and held fixed by a set-screw 51, is adapted to hold the friction wheel 44 in any desired position on shaft 45, by which, as 85 will be apparent, any desired speed of rotation of shaft 45 in either direction may be readily obtained. On shaft 45 is a gear 52 which meshes with a gear 53 on a vertical shaft 54 journaled in a side extension 90 55 of upright 13. The shaft 54 has thereon a gear 56 which meshes with a gear 57 fast on shaft 38, by which means shaft 38 is driven. The sleeve 37 has thereon a clutch member 58 with a hand wheel 59 thereon 95 which coöperates with a clutch member 60 splined on shaft 38 and controlled by a shifter lever 61 which is held in either operative or inoperative position by means of a latch bar 62.

From the foregoing the operation of our device will be apparent. By throwing clutch 60 out sleeve 37 may be operated by hand wheel 59 independently of the power drive to project or retract the boring bar. 105 When clutch 60 is thrown in, the sleeve 37 will be driven from shaft 38 by the friction disk 43 and train of worm gearing

above described, whereby the rack bar 33 will advance the boring bar at any desired rate of speed or retract it at any desired rate of speed. The entire drive of the device is in the highest degree simple and efficient. The essential element of a graduated and uniform advance of the boring or milling tool proportioned to the character of the work being done, is accomplished with absolute certainty. All of the parts are readily accessible and the machine is compact and operates with a minimum requirement of power. A spiral driving pinion 42 is located in the vertical plane of the axis of the boring bar and coöperates with the spiral gear 27 splined on the boring bar to rotate the boring bar at the required speed, and it does this with such constant application of power that the rotation of the bar is without vibration or chattering conduced to perfect work of the boring bar.

We claim:

A boring machine comprising a slidable and rotatable boring bar, a rack bar swiveled to the boring bar for sliding the same, a transverse driven shaft, a spiral pinion

secured to said shaft, a spiral gear splined on said boring bar, a friction disk on the end of said driven shaft, a longitudinal shaft, a friction wheel slidably and non-rotatably mounted on said longitudinal shaft for adjustable engagement with said friction disk, a gear secured to the rear end of said longitudinal shaft, a vertical shaft, a gear on said vertical shaft meshing with said last mentioned gear, a transverse shaft mounted at the rear of the machine, a gear on said transverse shaft meshing with the gear on the vertical shaft, a sleeve journaled on said transverse shaft, a pinion on said sleeve meshing with said rack bar, a clutch member on said sleeve, a clutch member splined on said transverse shaft, and means for moving the clutching members into clutching and unclutching position.

In testimony whereof we affix our signatures.
